**MACHINES FOR FORMING JOURNAL BOX
PACKING ROLLS**

James W. Brunner and Jack Cowan, Altoona, Pa.

Application February 10, 1955, Serial No. 487,374

2 Claims. (Cl. 100—87)

This invention relates to machines for forming journal box packing rolls, and more particularly relates to machines for forming packing rolls of the type used in lubricating the journals of railroad rolling stock utilizing "plain bearing" journals and journal bearings.

Journal box packing rolls are widely used throughout railroad systems as a means for lubricating journals and journal bearings of rolling stock where the so-called "plain bearings" are utilized. In practically all applications, such journal box packing is composed of either cotton waste, cotton textile, or combinations of cotton and wool waste, heavily impregnated with lubricating oil. The packing stock is generally formed into rolls which are placed side by side in the journal box, below the journal, so as to form a lubrication bed which wipes or rubs against the journal. The packing rolls are generally positioned transversely of the axis of the journal, with the innermost roll adjacent to the dust guard seat of the journal box. When it is desired to lubricate a journal and its bearing, oil is poured into the journal box and permeates through the packing to the periphery of the journal.

Journal packing is generally formed into rolls of varying sizes to accommodate the various sizes and types of journals and journal boxes currently in use.

Heretofore, journal box packing rolls have been made by hand. However, hand made rolls have not been fully satisfactory due to the difficulties encountered in attempting to form them of uniform size, texture and resilience. Regardless of the amount of skill and care exercised, experience has shown that it is virtually impossible to make packing rolls all of which have the same diameter, resilience and smoothness, and which are free of lumps. In addition, preparation of packing rolls by hand is a generally time consuming process.

The present invention is directed to a machine designed to overcome the difficulties enumerated above and to greatly expedite the production of journal box packing in roll form. It is accordingly an object of this invention to provide a machine for rapidly producing packing rolls of uniform size, resilience and smoothness, and which are free of lumps.

It is a further object of this invention to provide a machine for forming journal box packing into rolls of varying sizes to meet the requirements of the different types and sizes of journal boxes and journals currently in use.

It is a further object of this invention to provide a machine for forming journal box packing rolls incorporating a rotatable cylinder having a plurality of pockets for receiving the mass stock from which the rolls are formed, means for imparting rotary motion to the cylinder, an idler roller, an adjustable guide roller, an endless belt encircling the drums and rollers, and means whereby the adjustable roller may be selectively spaced from the cylinder to vary the slack of the belt proportionately to the size of the packing rolls being formed.

Other objects and advantages of this invention will be apparent from the following detailed description of a

preferred embodiment thereof, reference being had to the accompanying drawings wherein:

Fig. 1 is a side elevation of a preferred embodiment of this invention, partly broken away, showing one of the cylinder pockets in loading position.

Fig. 2 is a top plan view of the machine.

Fig. 3 is a longitudinal section taken along the line III—III of Fig. 2 and shows the manner in which a packing roll is formed upon clockwise rotation of the cylinder.

Fig. 4 is a longitudinal section taken along the line IV—IV of Fig. 2 and shows the manner in which the packing roll is removed upon counterclockwise rotation of the cylinder.

Fig. 5 is an enlarged view, partly broken away, of a retractable latch means with the latch pin extended to lock the drum against rotation.

Fig. 6 is an enlarged view, partly broken away, of a retractable latch means with the latch pin withdrawn to permit rotation of the drum.

Fig. 7 is a fragmentary perspective view showing the segmental helical cam surface on the left-hand end of the crank handle.

Fig. 8 is a fragmentary perspective view showing the opposing segmental helical cam surface on the latch pin knob.

Fig. 9 is an exploded view in perspective showing a preferred manner for securing the crank arm to the drum shaft.

Fig. 10 is a perspective view, partly broken away, showing the usual manner in which packing rolls are placed in a "plain bearing" journal box.

In the drawings, the numerals 10 and 11 denote, respectively, right- and left-hand housing side plates which, as will be explained, provide supports for the bearings of the various rotatable parts of the machine. Mounted between the side plates 10 and 11, on shaft 20, is a rotatable cylinder or drum 12 having a plurality of axially disposed pockets 13a, 13b and 13c. Each pocket is of a different size or content to accommodate different quantities of textile stock commensurate with the desired size and weight of the packing rolls to be formed.

As shown in Fig. 4, the cylinder 12 is formed from a plurality of elongated angles 14a, 14b and 14c and a plurality of cover plates 15a, 15b and 15c successively disposed between and contiguous with the elongated angles 14a, 14b and 14c. The cover plates are formed with lips 16a, 16b and 16c which overlap and are welded to the elongated sides of the angles 14b, 14c and 14a, respectively. It will be noted that the cover plates have arcuate segments 17a, 17b and 17c, formed on a radius having its center at the center of shaft 20, and depending convex segments 18a, 18b and 18c which terminate at and are welded to the inside corners of the angles 14a, 14b and 14c. In order to reinforce the cover plates 15a, 15b and 15c, stiffening angles 21 are welded to the insides thereof adjacent to the seams formed by the juncture of the arcuate and convex segments. A pair of end plates 19, having the cross-sectional configurations of pockets 13a, 13b and 13c cut therein, complete the construction of cylinder 12.

The shaft 20 is journaled in bearings 23 supported in the side plates 10 and 11. Rotary motion is imparted to the cylinder 12, through shaft 20, by means of a crank handle 24 and a crank arm 25. As shown in Fig. 9, the right-hand end of shaft 20 is formed with an extension 26 of polygonal cross-section and a protruding threaded stud 27, and the crank arm 25 is formed with a polygonal aperture 28. The crank arm 25 and the drum shaft 20 are assembled by sliding the shaft extension 26 through the aperture 28 and securing the same in place by means of the stud 27, appropriate washers and a nut,

A pair of bearing blocks 30, having a plurality of bearing notches 31, are spaced from the cylinder shaft bearings 23 in side plates 10 and 11. The notches 31 are inclined slightly in the direction of the cylinder, preferably at an angle of about 7° to the vertical. The notches 31 provide mountings for selectively spacing a rotatable guide roller 32 from cylinder 12. Disposed between cylinder 12 and roller 32 is a rotatable idler roller 33 journaled in bearings 34 supported by plates 10 and 11.

An endless belt 35 encircles drum 12 and rollers 32 and 33, and is of a texture adapted to provide friction on the cylinder and rollers sufficient to permit operation of the machine. The belt 35 is preferably made from Neoprene impregnated canvas duck, but may also be made of any fabric or mesh steel coated with Neoprene or suitable rubber, and is of a length sufficient to permit it to be depressed along the confines of one of the pockets 13a, 13b and 13c, as shown in Fig. 1.

The purpose of the guide or adjustable roller 32 is to vary the degree of slack on belt 35 proportionately to the size of the packing roll being formed. For each pocket of cylinder 12, roller 32 has a corresponding position in bearing blocks 30. In the particular machine illustrated in the drawings, provision has been made for the formation of packing rolls having diameters, respectively, of $3\frac{1}{4}$ inches, $3\frac{3}{4}$ and 4 inches. If it is desired to make a 4 inch roll, the largest pocket 13a is utilized and adjustable roller 32 is engaged in the notch 31 below which the scale indication "4" appears. If it is desired to make a roll of $3\frac{1}{4}$ inches, the smallest pocket 13c is utilized and adjustable roller 32 is engaged in the notch 31 having the scale reading of $3\frac{1}{4}$ inches.

Mounted on the outside of side plate 10 is a latch plate 36 concentric with shaft 20. A plurality of latch pockets 37, circumferentially spaced in latch plate 36, are adapted to receive a retractable latch pin 38 mounted internally of crank handle 24. In order to avoid excessive wear on latch plate 36, latch pockets 37 are reinforced by annular bushings 39. A spring 40 is normally adapted to urge the latch pin 38 into engagement with the latch pockets 37. A retractable latch means, comprising a knurled latch pin knob 41 having a contiguous segmental helical cam 42, cooperating with a second segmental helical cam 43 contiguous with the crank handle 24, serves to retract the latch pin 38 from the latch pocket 37 and to secure it in such retracted position by cooperation of the cam surfaces 44 and 45.

Load limit lines 46 are inscribed on the insides of side plates 10 and 11 for the purpose of indicating the amount of mass stock to be placed into the pockets 13a, 13b or 13c.

In order to secure the machine into a solid unit, a plurality of tie rods 49 having threaded ends are mounted internally of spacers 47 spaced from one another transversely of the machine, as best shown in Figs. 1 and 2. Nuts threaded onto the ends of the tie rods 49 serve to pull the side plates 10 and 11 firmly against the spacers 47, thereby assembling the machine.

The operation of the machine is as follows. For the purpose of explanation, it will be assumed that a packing roll having a 4 inch diameter is to be formed. The first step is to rotate the cylinder 12 until the crank handle is adjacent to the latch pocket bearing the indication "4", thereby positioning the largest pocket 13a immediately below the load limit line 46. The cylinder 12 is then locked into this position by releasing the latch pin knob 41 so as to permit the latch pin 38, under the force of spring 40, to engage the latch pocket 37. With cylinder 12 thus locked, the adjustable roller is positioned in the notch 31 having the scale reading "4". Belt 35 is then depressed into pocket 13a and mass packing stock 50 inserted into pocket 13a over belt 35 until the pocket is filled to the limit line 46, all as shown in Fig. 1. There-

upon, latch pin 38 is retracted and cylinder 12 rotated by means of crank handle 24 and crank arm 25, in a clockwise direction.

As shown in Fig. 3, the rotation of cylinder 12 in a clockwise direction will cause the mass stock to be ejected from the pocket 13a, between cylinder 12 and roller 33, and formed into a roll 51 as a result of the buffing action of the drum 12, belt 35 and roller 33. After the packing roll 51 has been properly formed, by continued rotation of cylinder 12 in a clockwise direction a suitable number of times, cylinder 12 is rotated counterclockwise causing the packing roll 51 to drop back into pocket 13a, from which it is ejected, to the left of the machine, over cylinder 12. The above procedure is adopted for the formation of packing rolls having different diameters, but it must be kept in mind that the adjustable roller 32 must be properly mounted in the bearing block 30 so that the slack on the belt 35 will correctly correspond to the pocket selected for forming the packing roll 51.

In order to provide drainage of the oil residue from the mass stock, drainage holes may be drilled in segments 17a, 17b and 17c of the cover plates 15a, 15b and 15c.

It will be understood, of course, that any desired number of pockets may be formed in the cylinder, including a single pocket, but it is essential that for each pocket of a varying size there be provided a corresponding notch in the bearing block 30 so as to furnish means to properly space roller 32 relative to cylinder 12 to provide the proper degree of slack on the belt 35 for forming a packing roll of the desired diameter.

It is to be further understood that the distance between the side plates 10 and 11 may be varied, with corresponding variation in the length of the drum, rollers, belt, etc., so as to permit the manufacture of packing rolls of any desired length.

While a preferred embodiment of this invention has been particularly described and illustrated, it is to be understood that various modifications and changes in the shape, size, proportion and arrangement of the parts may be resorted to without departing from the scope of the appended claims.

Having thus described our invention, we claim:

1. In a machine for forming journal box packing rolls from textile waste, a frame having laterally spaced upright side members; a cylinder affixed to a shaft rotatively borne in the frame members and provided with annularly spaced pockets of different sizes circumferentially thereof; a guide roll rotatively supported between the frame members at the top thereof laterally adjacent the cylinder; an endless belt trained about the cylinder and the guide roll with allowance of slack for depression of the belt into the individual pockets of the cylinder; an operating crank arm affixed to one end of the cylinder outwardly beyond one of the frame members; and retractable latch means on the crank selectively engageable into annularly spaced apertures in said one frame member to temporarily lock the cylinder against rotation with the respective pockets of the cylinder accessible from above for placement of the textile waste thereinto.

2. The machine of claim 1 further including an idler roll also rotatively supported between the frame members with capacity for being positionally adjusted to regulate the slack of the belt in accordance with the particular pocket of the cylinder being used.
